BILLIARD TABLE

David K. Walz, 4102 Eula Circle, Doraville, Ga.

Filed Sept. 13, 1962, Ser. No. 71,676

Term of patent 7 years

(Cl. D34—3)

FIG. 1

Des. 196,593

PAGE 2

FIG.2

Des. 196,593

FIG. 3

FIG. 4

FIG.5

FIG. 1 is a perspective view of the billiard table, embodying my new design.

FIG. 2 is an elevational view of the right end of the billiard table shown in FIG. 1.

FIG. 3 is an elevational view of the opposite end of the billiard table shown in FIG. 1.

FIG. 4 is a side elevational view. The opposite side is exactly the same as view shown in FIG. 4.

FIG. 5 is a top plan view.

I claim:

The ornamental design for a billiard table, as shown and described.
